UNITED STATES PATENT OFFICE.

LEON RUBAY, OF CLEVELAND, OHIO, ASSIGNOR TO THE WHITE COMPANY, OF CLEVELAND, OHIO, A CORPORATION OF OHIO.

DESIGN FOR AN AUTOMOBILE-BODY.

47,626.

Specification for Design.

Patented July 20, 1915.

Application filed March 19, 1915. Serial No. 15,610. Term of patent 7 years.

To all whom it may concern:

Be it known that I, LEON RUBAY, a citizen of the Republic of France, residing at 1559 East One hundred and fifteenth street, in Cleveland, Cuyahoga county, Ohio, United States of America, have invented a new, original, and ornamental Design for Automobile-Bodies, of which the following is a specification, reference being had to the accompanying drawings, forming a part thereof.

In said drawings, the figure is a side elevation of an automobile body showing my design.

I claim:

The ornamental design for an automobile body, as shown.

LEON RUBAY.
